UNITED STATES PATENT OFFICE.

FREDERICK C. WEBER, OF NEW YORK, N. Y.

PUMPING SYSTEM.

1,309,229.

Specification of Letters Patent.

Patented July 8, 1919.

Application filed August 1, 1918. Serial No. 247,806.

To all whom it may concern:

Be it known that I, FREDERICK C. WEBER, a citizen of the United States, and a resident of the city, county, and State of New York, 5 have invented certain new and useful Improvements in Pumping Systems, of which the following is a specification.

In my prior Patent No. 990,085, dated April 18, 1911, I have illustrated and described a pumping system wherein I have utilized compressed air and vacuum as a means for elevating water or other liquid from great depths. This system is particularly adapted for use in mines and deep oil 10 or Artesian wells. In my later Patent No. 998,059, dated July 18, 1911, I have shown the basic principle adapted for use in what I have called a suburban type or isolated pumping plant. This latter type is also 15 adapted for deep well pumping, but is of a type requiring more or less attention. In a still later Patent No. 1,136,070, dated April 20, 1915, I have introduced many improvements designed to render the system entirely 20 automatic and self-replenishing whenever any draft is made upon the system, so long as the pressure is maintained in the air receiver. I have found from experience that many of the elements of the latter form of 25 pump may be dispensed with, and by a simple rearrangement of the remaining elements, with certain slight changes made in some of them, I may accomplish substantially all of the results obtained by the 30 pumping system described in said patent.

My present invention is fully illustrated in the accompanying drawing wherein—

Figure 1 is a sectional diagrammatic view of my improved pumping system.

Fig. 2 is a sectional view of the compensating valve.

Fig. 3 is a plan view of the capacity disk.

Similar reference numerals refer to like parts throughout the specification and drawing.

The well casing 1 is a tube extending down into the well any desired distance, usually to some impervious stratum of rock or hardpan. Supported upon the top of the casing 1, is a cap 2, which is designed to carry the well tubing and parts which are suspended within the well. Upon the cap 2 rests a cap thimble or supporting casting 3, into the lower side of which the well tube 4 50 is screwed, the latter being made up of a sufficient number of sections connected by

unions 5, to reach to a point near the bottom of the well, or at least to a point considerably below the pumping water level, indicated by P. W. L. upon the drawing. At 60 the extreme lower end of the tube 4, I secure the usual intake valve 6. Between the adjacent ends of the tube sections next above the valve 6, and serving as a union to connect such sections together is the discharge 65 valve casting 7, which is provided with the cage 8 at one side of its center to contain the ball valve 9, the latter resting upon the seat 10. The casting 7 has the lateral passage 11 which expands above the cage 8 into 70 circular cross-section and carries at its upper end, the tube 12. At the upper end of the tube 12 is the diaphragm coupling casting 13, which serves as a support for the extension tube 14, the latter extending upwardly 75 to a point near the top of the well.

From the thimble 3, the smaller tube 15 is suspended and extends within the extension tube 14 to a point slightly above the casting 13.

Secured to the upper end of the thimble 3 is the T 16, in the upper end of which is the packing gland 17, through which latter the air pipe 18 runs leading from the air receiver 19 to and is tapped into the diaphragm casting 13. From the lateral spud of the T 16, the service pipe line 20 extends to the house plumbing system. Comparatively high air pressure is maintained in the receiver 19 by any suitable or desired air 80 compressor (not shown).

From the system of tubes and connections thus far described, it will be noted that two chambers are formed, which may be designated as the receiving or working chamber 95 A, formed by the valve 6, lower end of the tube 4, casting 7, tube 12 and casting 13; and the discharge chamber B, formed by the casting 7, tube 4, thimble 3, tube 12 and casting 13. These two chambers are separated 100 by the ball valve 9, which permits the free flow of water from chamber A to chamber B, but prevents a reverse flow.

The upper part of the well is enlarged to form a so-called frost pit 21, provided with 105 a suitable cover 22; the service pipe 20 is led through the wall of the frost pit below the frost line to connect with the house plumbing system. Within this frost pit, the otherwise exposed parts of the system 110 are located, and are fully protected from frost or other accident.

As a means for compensating for differential pressure in the two chambers A and B, as well as for voiding chamber B of excessive accumulation of air as hereafter explained, I provide a compensating valve 26, connected up in the pipe 27, leading from the chamber B and also having a small pipe connection with the service pipe line 20, through the T 16. The details of the 10 compensating valve are substantially the same as the regulating valve of my prior Patent No. 1,136,070, and are as follows:—

The valve consists essentially of the lower casting 30, the intermediate casting 31, and 15 the upper casting 32. The lower casting 30 is provided with the two chambers 33 and 34, separated by the diaphragm 35, having therein the passage 36. The upper side of the diaphragm 35 is formed into a valve 20 seat 37. Upon the upper side of the casting 30 is secured by means of the flange bolts 38, the casting 31, said casting being provided with the valve chamber 39 opening into the chamber 33, and separated 25 therefrom by means of the gauze screen 40. Within the chamber 39 is located the hollow valve plug 41, the lower end of which is provided with the leather packing 42 to bear upon the seat 37. The upper end of the 30 valve plug 41 is recessed as at 43, to receive the compression spring 44, the upper end of which bears upon the under side of the puppet valve 45. The puppet valve stem 46 extends upwardly through the casting 31, 35 and projects into an upper chamber 47 in said casting, and through a packing gland 48, the latter being interposed to make the stem airtight. Just above the valve 45 is the valve seat 49 at the lower end of the 40 small chamber 50. An exhaust port 51 leads from the chamber 50 to the open atmosphere.

The upper part of the casting 31 is hollowed out as at 52 to form a shallow chamber, from which the passage 53 leads and is in communication with the service pipe line 20 through the pipe 28 and T 16. The chamber 52 is formed by means of the flexible diaphragm 54, made of sheet rubber, 50 specially treated leather or other suitable material impervious to water. The diaphragm 54 is held in position by the flange 55 of the upper casting 32 through the medium of the bolts 56. Secured to the central 55 portion of the diaphragm 54 is a downwardly extending boss 57 which enters the chamber 47. Upon the upper side of the diaphragm 54 is secured the flat spring seat 58 with its upwardly projecting boss 59, for 60 supporting the lower end of the compression spring 60. The spring cap 61 is located upon the upper end of the spring 60, and the cap is provided with marginal slots taking over the internal guide ribs 62 so as 65 to prevent rotation of said cap. The com-

pression of the spring 60 is effected by means of the screw 63 which is screwed into the central aperture of said cap and provided with a collar 64 which bears upon the under side of the dome-like top of the 70 casting 32. The upper end of the screw 63 projects outside of the dome and is squared as at 65, so that it may be turned when it is desired to adjust the compression of the 75 spring 60.

The plug valve 41 is made to move easily within the chamber 39, with a very slight clearance, so that air pressure coming through the pipe 27 may gradually find its way from said chamber 33 to chamber 39 80 so as to equalize both above and below the valve plug 41; or if preferred, the valve plug may be made to fit the chamber 39 quite closely, and the leakage from chamber 33 to chamber 39 provided for by the small 85 by-pass 66 in the plug 41.

The discharge chamber 34 has a pipe 67 leading from it, in which the globe valve 68 is placed. At starting, it is desirable that pressure in chamber B should build 90 up quickly by the rising liquid therein against the confined air in the upper part of the chamber; this is accomplished by closing the valve 68 for a short time. At other times it may be found that the voiding of 95 chamber B of surplus accumulations of air takes place too quickly for efficient operation, or that too much escapes at one time; the discharge may then be cut down by means of the valve 68. 100

In order that the supply of air pressure from the receiver 19 to chamber A may not be too rapid, the capacity disk 18' is placed in the pipe 18. This disk is of sheet metal of a diameter the same as the abutting 105 flanges of the sections of the pipe 18, between which it is inserted and held. The disk has a central aperture 18'' through it, which is materially smaller than the bore of the pipe 18. The diameter of said aperture is determined by the length and capacity of chamber A and in a measure, by the depth of its submergence below the P. W. L. By its use a retarded flow of pressure from the receiver to chamber A takes place when 110 a considerable portion of the air in the chamber escapes to chamber B, as hereafter explained.

The operation of the system is as follows:— 120

Pressure in the receiver 19 is maintained at a point sufficiently high to overcome the hydrostatic pressure of the well column; that is to say, receiver pressure should be equal to or slightly in excess of the water 125 pressure at the intake valve 6, to insure the depression of the water level within chamber A to or below valve 9. Automatic air compressors for this and kindred purposes are in common use and need no description 130

herein. With the lower end of the well tube, its intake valve 6 and chamber A submerged to a considerable depth below the P. W. L., water will rise at the start in the chambers 5 A and B to the P. W. L. The valve 68 is now closed and pressure from the receiver 19 is turned on. As soon as the compressed air is applied to chamber A, the water therein will be displaced by the air and forced 10 past the valve 9 into chamber B. A portion of the air will ascend with the water discharged into chamber B at an increased velocity inasmuch as the air is about 700 or 800 times lighter than the water and is therefore more buoyant. The escape of air from chamber A will result in an appreciable drop of pressure therein, owing to the fact 15 that the restricted passage through the capacity disk 18' prevents a too rapid replenishing of pressure from the receiver, and as soon as such pressure falls below the hydrostatic pressure of the outside or well column, water will again enter chamber A through the intake valve 6 until the air pressure 20 therein equals or exceeds the outside or hydrostatic pressure, when of course the intake valve 6 will again close. The discharge of water from chamber A to chamber B past valve 9 will take place as rapidly as it is 25 drawn from the service pipe line 20 through the house plumbing system. These periodic discharges take place as often as the water in chamber A is depressed to the level of the discharge valve 9, and in case of a continuous draft from the house plumbing system, they give the appearance of a continuous stream. Their intermissions are barely 30 perceptible to the naked eye.

As the air accumulates in the upper part 40 of chamber B, some means must be provided for disposing of the excess or surplus. This means is found in the compensating valve 26. Drafts of water from the service pipe line 20 will lower the pressure therein and 45 throughout the system back as far as valve 9. This lowering of pressure extends into chamber 52 through pipe 28, thereby permitting the spring 60 to react upon the diaphragm 54, which results in unseating the puppet valve 45 and exhausting chamber 39. The differential pressure beneath the plug 50 valve 41 will now become effective to unseat said valve and vent the pipe 27 to the atmosphere to a point where equilibrium is again 55 restored in chamber B by accumulating pressure due to the rapid influx of water from chamber A; this will extend through pipe 28 and restore diaphragm 54, thereby permitting puppet valve 45 to again seat, and 60 thus close chamber 39. Pressure will now accumulate in chamber 39 and in conjunction with the spring 44, close the plug valve 41, thereby preventing the escape of more air from chamber B than is necessary to 65 properly restore equilibrium.

The extension of the tube 14 so far above the lower end of the tube 15, effectually prevents any of the rising bubbles of air from escaping into the service pipe line 20.

The whole operation as above described 70 is very quickly performed, and the system is entirely automatic; it requires no attention beyond an occasional inspection to see that all joints are air and watertight, and the parts are otherwise operating satisfactorily.

In practice, the chambers A and B are called the working chamber and the discharge chamber respectively; in the appended claims I have used these terms as 80 more conveniently referring to the two chambers as well as for the reason that they are correctly descriptive of their functions.

I claim:—

1. In a pumping system, the combination 85 of a working liquid chamber, a retarded fluid pressure supply therefor, a combined air and liquid discharge chamber having a valved connection with said working chamber, a normally closed discharge pipe leading 90 from said discharge chamber below the normal liquid level therein, and a differential pressure actuated compensating valve connected to said discharge chamber and to said pipe, whereby liquid is alternately 95 drawn into said working chamber and discharged therefrom together with a portion of the pressure medium therein into said discharge chamber, and excess accumulations of air therein are exhausted therefrom as 100 and when liquid is drawn from said discharge pipe.

2. In a pumping system, the combination 105 of a source of fluid pressure supply with a working liquid chamber normally submerged in liquid to be pumped, a pipe leading from said supply to said chamber said pipe having a restricted passage for retarding the flow of pressure medium therethrough, a discharge chamber having a valved connection 110 with said working chamber, a normally closed discharge pipe leading from a point below the liquid level in said discharge chamber and a differential pressure actuated compensating valve having pipe connections with the air space in liquid chamber and with said discharge pipe respectively, whereby liquid is alternately drawn into 115 said working chamber and discharged therefrom together with a portion of the fluid 120 pressure medium into said discharge chamber, and excess accumulations of said fluid pressure medium are exhausted from said discharge chamber as and when fluid is drawn from said discharge pipe.

3. In a pumping system, the combination 125 of a source of fluid pressure supply with a working chamber provided with an intake and a discharge valve normally submerged in liquid to be pumped, a pipe connection 130

4 having a restricted passage therein, leading from said supply to said chamber, a closed discharge chamber communicating with said working chamber by way of said discharge valve, and means for compensating differentials of pressure in said chambers.

5 4. In a pumping system, the combination of a source of fluid pressure supply, a working chamber normally submerged in liquid to be pumped, said chamber being provided with an intake valve and a discharge valve at its lower end, a pipe connecting said supply with the upper end of said chamber, a discharge chamber communicating with said 10 working chamber by way of said discharge valve, a discharge pipe leading from said discharge chamber below the normal liquid level therein, and a compensating valve connected with said chamber for exhausting it of excess accumulations of fluid pressure 15 medium escaping thereto from said working chamber.

20 5. In a pumping system, the combination of a working chamber having valved inlet and discharge passages at its lower end, said inlet passage being normally submerged in liquid to be pumped, means for causing a continuous condition of air pressure within said chamber, a closed discharge chamber 25 communicating with said first named chamber by way of said discharge passage, whereby the liquid is transferred under said air pressure from said working chamber to said discharge chamber, and means for exhausting 30 a limited portion of the air from said discharge chamber which escapes thereto from said working chamber.

35 6. In a pumping system, the combination of a working liquid chamber, and a normally closed discharge chamber with a valved passage therebetween, a source of fluid pressure supply having a restricted passage therein leading to said working chamber, for depressing the liquid level therein to or below 40 said valved passage, whereby a portion of the air pressure from said working chamber escapes to said discharge chamber, and a compensating valve connected with said discharge chamber and actuated by differential 45 pressures in various parts thereof for exhausting excess accumulations of air therefrom.

50 7. In a pumping system, the combination of a working liquid chamber, having a valved inlet and a valved discharge passage, a source of fluid pressure supply leading through a restricted passage to said working chamber, a normally closed discharge chamber, connected with said discharge 55 passage, and a compensating valve connected to said discharge chamber, actuated by differences of pressure in different parts thereof for voiding said discharge chamber of excess accumulations of fluid 60 pressure.

65 8. In a pumping system, the combination of a working liquid chamber having a valved inlet and a valved discharge passage at the lower end thereof, a source of fluid pressure supply connected to the upper end 70 of said chamber and having a restricted passage in said connection, whereby the liquid may be discharged from the said discharge passage under said pressure and thereafter a portion of the accumulated pressure may 75 also exhaust therefrom to permit the influx of liquid and thereby replenish said chamber.

80 9. In a pumping system, the combination of a discharge chamber, having a valved passage at its lower end and a normally closed discharge pipe extending into said chamber to a point below the normal liquid level therein, means for forcing liquid under pressure into said chamber through said valve passage, and a compensating device connected to said chamber above the liquid level therein and to the said discharge pipe, said compensating valve being actuated by a momentary reduction of pressure in said 85 pipe to void said chamber of any excess accumulation of fluid pressure.

85 10. In a pumping system, the combination of a source of air pressure supply, a working chamber having an intake valve submerged 90 in liquid to be pumped, a pipe having a restricted passage therein leading from said supply to said chamber, a discharge chamber having a valved connection with said working chamber, a normally closed discharge 95 pipe extending into said discharge chamber to a point below the normal liquid level therein, thereby forming a closed air chamber in the upper part thereof, and a compensating valve for voiding said air chamber 100 of surplus air accumulations therein from said working chamber, said valve having a discharge connection with said air chamber and a closed pressure pipe connection with 105 said discharge pipe.

11. In a pumping system, the combination of a closed chamber having its lower end provided with an inlet valve, a normally closed discharge pipe leading from said chamber below the normal water level therein, means for introducing air and water under pressure into said chamber through said inlet valve, and a compensating valve connected to the upper end of said chamber and to said discharge pipe, and actuated by momentary differences in pressure between 115 said chamber and pipe to void said chamber of excess accumulations of air, as when said pipe is opened to draw water therefrom.

12. In a pumping system, the combination of a tubular chamber closed at the top, and having a valved inlet at the bottom, said chamber being partially submerged in liquid to be pumped, a normally closed discharge pipe extending into said chamber to 125 130

a point below the normal liquid level therein, means for forcing liquid under air pressure into said chamber through said valved inlet, and means actuated by the momentary 5 drop of pressure in said pipe due to drawing liquid therefrom for voiding said chamber of excess accumulations of air.

13. In a pumping system, the combination of a tubular chamber closed at the top and 10 extending into a body of liquid to be pumped, a normally closed discharge pipe

leading from a point in said chamber below the normal liquid level therein, means for introducing air under pressure into the bottom of said chamber to produce an air lift 15 therein, and means actuated by the momentary drop of pressure in said discharge pipe due to drawing liquid therefrom for voiding the upper part of said chamber of excess accumulations of air.
